(57) **CLAIM**

The ornamental design for a bar handle, as shown and described.

DESCRIPTION

FIG. 1 is a top front right side perspective view of the bar handle showing of my new design;

FIG. 2 is a bottom rear left side perspective view thereof;

FIG. 3 is a top rear left side perspective view thereof;

FIG. 4 is a bottom front right side perspective view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

The broken lines in the drawings illustrate portions of the bar handle which form no part of the claimed design.
